UNITED STATES PATENT OFFICE.

MARTIN H. HALLORAN, OF PITTSBURG, PENNSYLVANIA.

LUBRICATOR FOR ELEVATOR-ROPE OR THE LIKE.

SPECIFICATION forming part of Letters Patent No. 709,318, dated September 16, 1902.

Application filed August 7, 1901. Serial No. 71,135. (No model.)

To all whom it may concern:

Be it known that I, MARTIN H. HALLORAN, a citizen of the United States of America, residing at Pittsburg, in the county of Allegheny and State of Pennsylvania, have invented certain new and useful Improvements in Lubricators for Elevator-Ropes or the Like, of which the following is a specification, reference being had therein to the accompanying drawings.

This invention relates to certain new and useful improvements in lubricators, and relates more particularly to lubricators employed for lubricating elevator-cables and such cables as are employed in cranes, hoists, lifts, and the like.

The object of the present invention is to construct a lubricator of the above-described class that will be extremely simple in construction, strong, durable, comparatively inexpensive to manufacture, and highly efficient in its use.

The invention still further contemplates the construction of a lubricator that will effectually retain the lubricant, except such portion as is taken up by the cable, irrespective of the speed of travel of the cable.

With the above and other objects in view the invention consists in the novel combination and arrangement of parts to be herein-after more fully described, and specifically pointed out in the claim.

In describing the invention in detail reference is had to the accompanying drawings, forming a part of this specification, and wherein like numerals of reference indicate corresponding parts throughout the several views, in which—

Figure 1 is a side elevation of my improved lubricator as it appears when secured in position to lubricate the elevator-cables. Fig. 2 is a front view thereof, the lubricator being shown in section. Fig. 3 is a side elevation of the pulley, the cables, parts of the pulley-frame being broken away, and my improved lubricator, the same being shown in longitudinal vertical section. Fig. 4 is a perspective view of the spring upon which the feed-roller is mounted.

In the drawings the reference-numeral 1 indicates a pulley-wheel, and 2 indicates the elevator-cables passing over the same.

The reference-numeral 3 indicates the lubricator, which has formed therein a lubricant receptacle or well 4, and 5 indicates the lubricant. In this lubricant receptacle or well are secured springs 6, carrying seats 7, in which is rotatably mounted a feed-roller 8, said springs normally tending to bear the periphery of the feed-roller against the cables 2 and lubricate the same when the cables are in operation. The reference-numeral 9 represents guards formed integral with the opposite ends of the lubricator-well 4, these guards being approximately semicircular in cross-section and designed to partially inclose the wheel and prevent the lubricant from being directed outwardly from the receptacle and further serve the purpose of retaining the small particles or drippings from the cables, which are directed to the lubricant receptacle or well, as will be readily understood. At the rear portions of these flat springs 6 are downwardly-extending lugs 10, secured to the sides for the purpose of securing the springs to the walls of the receptacle.

The many advantages obtained by the use of my improved device will be readily apparent from the foregoing description, taken in connection with the accompanying drawings, and it will be noted that various changes may be made in the details of construction without departing from the general spirit of my invention.

Having fully described my invention, what I claim as new, and desire to secure by Letters Patent, is—

In a lubricator, the combination with a lubricant-receptacle, of a pair of upwardly and outwardly extending curved guards, formed integral with the opposite ends of the said receptacle, said guards being approximately semicircular in cross-section and adapted to snugly inclose a portion of pulley-wheel, and a roller mounted in the said receptacle, substantially as described.

In testimony whereof I affix my signature in the presence of two witnesses.

MARTIN H. HALLORAN.

Witnesses:

JOHN NOLAND,
E. E. POTTER.
